UNITED STATES PATENT OFFICE

101,282

DESIGN FOR A RAIL BENDER

Ian D. Marsh, Belleville, Ill.

Application June 1, 1936, Serial No. 62,921

Term of patent 14 years

To all whom it may concern:

Be it known that I, Ian D. Marsh, a citizen of the United States, residing at Belleville, county of St. Clair, State of Illinois, have invented a new, original, and ornamental Design for a Rail Bender, of which the following is a specification, reference being had to the accompanying drawing, forming a part thereof, in which—

Fig. 1 is a plan view of a rail bender showing the top of my new design.

Fig. 2 is a bottom plan view.

Fig. 3 is a side elevation looking toward the underside of Fig. 1.

Fig. 4 is a side elevation looking toward the underside of Fig. 2.

Fig. 5 is an end elevation looking toward the right end of Fig. 3.

Fig. 6 is a detached perspective view of the depending part shown in elevation midway between the ends of Figs. 1 and 2, respectively.

I claim:

The ornamental design for a rail bender as shown.

IAN D. MARSH.
